UNITED STATES PATENT OFFICE.

JAMES D. REED, OF EAGLE, MICHIGAN.

TIMING DEVICE.

1,345,402.

Specification of Letters Patent.

Patented July 6, 1920.

Application filed May 2, 1919. Serial No. 294,168.

To all whom it may concern:

Be it known that I, JAMES D. REED, a citizen of the United States, and residing at Eagle, in the county of Clinton and State 5 of Michigan, have invented a new and Improved Timing Device, of which the following is a specification.

This invention relates to means for closing the electric circuits to the several spark 10 plugs of multi-cylinder internal combustion engines, and the object of my invention is to provide a timing-ring and a cap therefor wherein the wire and posts are absolutely protected from water and other undesirable matter.

In the accompanying drawing, Figure 1 is an elevation and Fig. 2 is a vertical section of a spark timer especially adapted for the engine of a Ford automobile. Fig. 3 is 20 a section on the line 3—3 of Fig. 2. Figs. 4 and 5 are sections on the lines 4—4 and 5—5 respectively of Fig. 3.

Similar reference letters refer to like parts throughout the several views.

25 In automobiles where the timing devices of the engines are so placed that rain can be thrown onto them and where the binding posts of the contacts are exposed, short-circuiting often takes place, sufficiently to 30 stop the engine. This is especially true in many vehicles where the timer is mounted at the front end of the cam shaft where it is often deluged with water when rain drives against the front of the radiator. To prevent such short-circuiting, I have provided 35 a combined cap and timing ring which may be mounted on many of the engines now in use.

In the present construction the base 1 40 with the rotating shaft 2 mounted therein, the head 3 mounted on the end of this shaft and positioned in any desired manner, a key 4, washer 5 and nut 6 being shown, are old and well known. Any other means for 45 positioning the head 3 on the shaft may be employed. A circular spring 7 may be mounted within the circular flange 8 on the base to insure a proper circuit between the base and the head 3.

50 A contact lever 9 carries a roller 10 at one end, the opposite end 12 being connected to a finger 13 on the head 3 by means of a spring 14 to hold the roller 10 outwardly. The construction thus far explained when 55 taken alone forms no part of my invention.

The cap 16 shown in the drawing has a

circumferential flange 17 which centers the timing ring 18, substantially L-shaped in cross section, and a metal ring 19 whose cylindrical flange 20 fits into the flange 8 60 on the base. The flange 21 on the timing ring centers it within the cap. Screws 22, particularly shown in Fig. 5, serve to hold the parts together. An arm 23 of any desired construction presses the cap toward 65 the base. The cap may have a lug 24 provided with a hole 25 to receive any desired connector whereby the cap may be turned to "advance" or "retard the spark."

Mounted in the timing ring 18 are a number 70 of contacts 26, one for each cylinder of the engine, and each preferably integral with a stem 27 that extends through the timing ring (Fig. 4) and has nuts 28 on its outer end between which the end of a circuit 75 wire 31 may be secured. The cap may have a hollow neck 29 through which the circuit wires extend and then pass around the body of the contact ring to the stems 27, preferably to around the screws 22, in the circular chamber between the timing ring and the cap.

The flange 21 on the timing ring fits 80 within the flange 17 on the cap. After the parts are secured together the circular 85 chamber between the ring 18 and the cap and the neck 29 of the cap are poured full of some non-conducting fusible material 30, such as rosin, which, when hard, will incase and seal all the parts in proper position. 90 The wires 31 outside of the cap may be protected by means of rubber tubing 34 extending over the neck 29 as shown in Fig. 2 or into it as shown in Fig. 1.

It will be seen that the wires 31 are entirely inclosed and that the danger of short-circuiting because of rain is substantially 95 eliminated.

The details and proportions of the various parts may all be changed by automotive 100 engineers without departing from the spirit of my invention.

I claim:

1. In a timing device for internal combustion engines, the combination with the 105 base and the timing shaft supporting a contact roller, a cap having a hollow neck, a non-conducting timing ring L-shaped in cross section secured within the cap and forming two walls of a circular conduit, a 110 series of contact plates mounted therein in the path of said roller, a stem for each con-

tact plate extending through the ring, wires connecting to said stems and extending out through the neck on the cap, and fusible non-conducting material filling the space between the timing ring and the cap and in which the wires are embedded.

2. In a timing device for internal combustion engines, the combination of a flanged base and a timing shaft supporting a contact roller, a cap having a hollow neck, an L-shaped non-conducting timing ring secured within the cap and so formed as to leave a circular chamber, a series of contact plates mounted in the ring in the path of the roller, a stem for each contact plate extending through the ring into said circular chamber, a wire extending from each stem out through the neck of the cap, fusible non-conducting material filling the circular chamber and neck of the cap and in which

the wires are embedded, a bearing ring mounted in said cap and having a flange fitting the flanged base, and means to secure the cap, timing ring and bearing ring together.

3. A cap for a timing device comprising a body having a cylindrical flange and a hollow neck, a timing ring of substantially L-shaped cross section fitting within the flange of the cap so as to leave a circular chamber between them, a series of contact plates carried by the timing ring, stems connected to said plates and extending radially through said ring, screws to secure the ring in position, wires extending from said stems around the ring and out through said neck and insulating material filling said circular chamber and embedding the wires and the ends of said stems.

JAMES D. REED
